UNITED STATES PATENT OFFICE.

HARRY G. MILLER, OF DENVER, COLORADO, ASSIGNOR TO MILLER SERVICE TOOL CO., OF MILWAUKEE, WISCONSIN, A CORPORATION OF WISCONSIN.

GRINDING MACHINE.

Application filed January 2, 1926. Serial No. 78,838.

My invention relates to improvements in grinding machines, more particularly for grinding milling cutters and cutters used in valve reseating operations.

5 The object of this invention, generally expressed, is to provide a machine of this class which shall be simple in construction, economical in cost, reliable, durable and efficient.

In machine work generally and in automobile repair shops in particular, it is frequently necessary to employ cutters for the purpose of producing angularly inclined seats for valves and other parts. Cutters of this type may be used for cutting any angle desired, but for automobile valve reseating operations are usually employed for cutting 15, 30, 45 and 60 degree angles. When cutters of this type become dull, it is necessary to regrind them. The regrinding operation

20 has heretofore been considered to be a very difficult one as each tooth has to be ground separately and with such accuracy that the corresponding points on all of the teeth will be exactly the same distance from the center. Each tooth must also be given the proper clearance so that it will be effective in its operation. In conical cutters of the type that I intend to grind on my improved machine the teeth come very close together

25 at the end having the smallest diameter. This makes it necessary to exercise the utmost care in grinding in order to obtain the desired clearance without striking the cutting edge of the adjacent tooth.

30 The improved grinding machine that forms the subject of this invention, briefly described, consists of a base member to which an electric motor has been attached. A grinding wheel of emery or other abradant material is supported on a bracket secured to the base and is rotated about an axis parallel with the axis of the motor, a belt or other suitable power transmitting means being employed to transmit power from the motor to the grinding wheel. An upwardly extending arm is supported by two spaced brackets or lugs that extend upwardly from the base. This arm is rotatable or oscillatable about an axis that lies in the plane of the grinding wheel and is also movable along said axis towards or away from the grinding wheel. The upper end of the arm has a flat disk like surface provided with an upwardly extending central pivot which is adapted to

several spindles for the reception and support of the cutters to be ground.

Having thus briefly described the structure of my improved cutter grinding machine, I will now proceed to describe the construction and mode of operation in detail, reference for this purpose being had to the accompanying drawings in which the preferred embodiment thereof has been illustrated and in which:

60 Fig. 1 is a top plan view of my improved machine showing the same adjusted for grinding a forty-five degree cutter;

Fig. 2 is a section taken on line 2—2, Fig. 1;

Fig. 3 is a section taken on line 3—3, Fig. 70 1; parts being shown in elevation;

Fig. 4 is a section taken on line 4—4, Fig. 3, and shows the parts adjusted for a thirty degree cutter;

Fig. 5 is a section similar to that shown in Fig. 4 but shows the parts adjusted for grinding a sixty degree cutter; and

Fig. 6 is a section similar to those shown in Figs. 4 and 5, but showing the parts adjusted to grind a fifteen degree cutter.

80 Figure 7 is a detail view of the stop screw 32 and associated parts.

In the drawings numeral 5 designates the base upon which is mounted and secured an electric motor 6. Also, mounted upon the base is a frame member or bracket 7 which extends upwardly above the motor and in which is journalled the shaft 8 upon which is mounted, so as to rotate therewith, a grinding wheel 9 of emery, carborundum or any other suitable abradant. Secured to the motor shaft 10 so as to rotate therewith is a pulley 11 which is relatively large and connected by a belt 12 with the pulley 13 on the grinding wheel shaft 8. When the motor

90 operates the grinding wheel will be rotated at a high speed. Extending upwardly from the base member directly in front of the grinding wheel so as to be bisected by a plane passing through the middle of this wheel are two lugs 14 and 15, the former of which has a cylindrical opening 16 whose central axis is parallel with the plane of rotation of the wheel 9 and which preferably lies in the plane of the center of the wheel. The lug 15 has a threaded opening 17 whose axis coincides with the axis of the opening 16. A threaded tubular member 18 has a hand wheel 19 secured to one end and cooperates with the threads on the walls of the opening 17 so that

110

85

90

95

100

105

110

when it is rotated it will move towards or away from the lug 14, as the case might be. A pivot or shaft 20 has one end provided with a cylindrical part 21 that fits into the opening in member 18 and extends entirely through this member in the manner shown in Fig. 3. The other end of shaft 20, which has been designated by numeral 22, is somewhat larger in diameter than the part 21 and has an axial opening 23. The tubular end 22 extends into the opening 16. A spring 25 has one end abutting the bottom of the opening 23 and the other the bottom of the opening 16. This spring is under compression and produces a force which tends to hold the shoulder 26 in contact with the inner end of the screw 18. It is now evident that by rotating the screw 18, the shaft 20 may be moved in the direction of its axis. The screw 18 moves the shaft 20 positively in one direction and the spring 25 returns it. Directly underneath the shaft 20, the base 5 has an opening 27 whose function will hereinafter appear. An arm 28 has a hub portion 29 that is provided with an opening of the proper diameter to receive the tubular part 22 and is clamped in position on the latter by means of the set screws 30. The length of the hub 29 is less than the distance between the adjacent surfaces of the lugs 14 and 15 and may therefore be moved in one direction or the other until its ends come into contact with the adjacent surface of one of the lugs 14 or 15. An arm 31 extends downwardly from the under side of the hub and terminates within the opening 27. A screw 32 extends through a threaded opening in this arm and serves as an adjustable stop which limits the extent of oscillation of the arm 28. The upper end of the arm 28 is provided with a flat circular part 33 whose upper surface is plane. A stud 34 projects upwardly from the center of the part 33 and extends perpendicularly with the upper surface thereof. A part that may be termed a turret head has a circular base 35, the lower side of which has an annular plane surface 36 that is adapted to rest upon the plane upper surface of the part 33. From the upper surface of member 35 a central cylindrical member 37 extends. This member has an axial opening 38 extending the entire distance from the lower surface of member 35 to the upper end of this member. This opening is of the proper size to receive the stud 34. The upper end of this opening is of somewhat smaller diameter than the lower and is threaded in the manner indicated at 39, for the reception of the threaded end of the screw 40, which serves to hold the tubular cylinder member 41 in place. The screw 40 has a knurled head 42 by means of which it may be rotated. The part marked 41 has a cut 43 extending inwardly from one side and a cylindrical opening 44 which intersects the axial opening through which the screw 40

passes. A rod 45 extends through the opening 44 and has one side flattened slightly in the manner indicated by numeral 46. This flattened portion engages the screw 40 and serves to prevent the rod 45 from rotating. Secured to the outer end of the rod 45 is a spring wire 47 whose function will appear as the description proceeds. Extending outwardly from the vertical cylindrical part 37 are three cylindrical shafts or bearings A, B and C. It will be noticed that the shaft marked "A" is the only one that extends radially from the center of member 37. The other two bearings B and C are tangent to circles whose centers coincide with the center of the stud 34 and whose radii are different. The reason for this feature of the construction will be hereinafter explained. The supporting member 33 has a U-shaped clamp secured to its under side in the manner shown in Fig. 3. The upper arm of this member extends inwardly over the upper surface of the base 35 and is provided with a clamping screw 49. The base 35 has a notch 50 cut in its outer edge so that the upper end of the clamp 48 may be passed in applying and removing the rotatable turret member. A number of holes 51 are provided in the part 35 for the reception of a pin 52. This pin is adapted to engage one of the holes 51 and a similar hole in the lower member so as to positively align the two parts and hold them in position while the cutter is being ground.

I will now describe the operation of grinding a cutter. Let us assume that it is desired to grind a forty-five degree cutter such as the one shown in Fig. 1 and designated by the reference character A¹. This cutter is put into place on the bearing A. If the hole in the cutter is larger than the bearing a bushing 53 is employed in the manner shown. The parts 33 and 35 are then rotated until the line marked 45° (Fig. 3) coincides with the zero line on the stationary member 33 after which the pin 52 is inserted into the opening 51 that is now aligned with the corresponding opening in the part 33, after which the screw 49 is tightened so as to clamp the parts firmly together. The axis of the shaft A will now make an angle of 45° with the axis about which the grinding wheel 9 rotates and since the arm 28 oscillates about an axis that lies parallel with the plane of rotation of the wheel 9, it is evident that every point in the cutter tooth will oscillate in a plane that is perpendicular to the plane of rotation of the wheel 9; therefore, if the position of the cutter is adjusted by means of the screw 18 until the edge of a tooth comes into contact with the cutting surface and if the parts are then oscillated about the axis of the screw 18, the wheel 9 will cut a surface that makes forty-five degrees with the axis of the cutter. The wire 47 engages the front side of the teeth and holds the cutter in the proper position. One

requisite to exact work is that when the oscillatory arm 28 is in the vertical position, the plane that passes through the middle of the grinding wheel 9 shall bisect the tooth to be ground so that in the grinding, the arm 28 can swing the same angular distance to both sides of the vertical. In this way the surface that is ground will be more nearly perfect than if other conditions prevailed.

10 In order to enable this adjustment to be obtained with cutters of different angularity, the shafts or bearings B and C have their axes spaced from the axis about which they rotate.

15 In my improved machine, the bearings of the upright arm or column 37, whose axes all lie in a plane cutting the axis of the column at right angles, are constructed for use with cutters of different angularity and so as to

20 bring each cutter into proper relation with the grinding wheel, by a resort to two expedients, one of which consists in varying the position of the axes of the different bearings with reference to the axis of the column, while

25 the other consists in varying the distance of the shoulders of the different bearings from the center or axis of the column. In my improved machine both of these expedients are resorted to and by such a combination it is believed the best commercial results in a machine of this character may be obtained.

30 The ideal position for grinding cutters is to have the cutter in such relation with the grinding wheel that the central plane of rotation of the grinding wheel shall bisect the teeth of each cutter when the latter is in the normal or central grinding position, and the variation in the position of the axes of the bearings with reference to the axis of the column, and the variation in the distance of the shoulders of the various bearings from the center of the column are resorted to with this end in view.

35 Referring now to Figure 6 in which the central plane of the grinding wheel does not bisect the tooth of the cutter as the structure is shown, I wish to call attention to the fact that if the shoulder of the collar 54 were made somewhat longer so that the cutter would be moved somewhat farther from the center of the column or arm 37, the teeth of the cutter shown in Figure 6 would be bisected by the central plane of the grinding wheel. In this case, of course, it would be necessary 40 through the instrumentality of the feed screw 18, to move the support 35 away from the grinding wheel in order that the cutter might be moved into such ideal grinding relation. This illustration indicates that the distance 45 of the shoulders of the bearings from the center of the column is an important feature.

45 Let us now consider Fig. 4 where a thirty degree cutter C¹ is shown. The axis of the bearing or shaft C, instead of intersecting the axis of the part 37, passes to the right there-

of so that the central portion of the surface to be ground lies in the central plane of the grinding wheel when the arm 28 is vertical.

The bearings A, B and C are provided with shoulders 53A, 53B and 53C, respectively 50 which hold the cutters from sliding inwardly.

In Fig. 6 I have shown a fifteen degree cutter secured to the bearing C. This has been accomplished by applying a collar 54 to the bearing. Similar collars may be provided whenever necessary for the purpose of bringing the cutter into the position necessary for obtaining the best results.

I will now explain how the proper clearance is obtained and for this purpose reference will be had more particularly to Fig. 3.

In this figure the cutter has been shown partly by dotted lines and partly by full lines. The tooth that is being ground has been designated by numeral 55. The horizontal line 85

marked C⁹ passes through the center of the grinding wheel and the line 56 represents the trace of a plane that contains the axis of the bearing A. If the lines C⁹ and 56 were on the same level, then the ground surface would

90 be inclined slightly inwardly and forwardly with the result that there would be no tendency for the teeth to cut. By raising the line 56 so that it will lie a short distance above

95 the center line C⁹, the cutting edge will be given the proper clearance. It is obvious, however, that if line 56 were raised too far above C⁹ that the periphery of the wheel 9 would come into contact with the cutting edge

100 of the tooth directly beneath. The machine is so constructed that with a grinding wheel of the maximum diameter, the desired clearance will be obtained without striking the cutting edge of the next tooth.

In operating the device the cutter is first 105 applied to the proper bearing and the upper edge of one of the cutter teeth brought into contact with the end of the spring 47. By

means of the screw 18 the cutter is moved towards the grinding wheel until it comes into 110 contact therewith so as to give the desired depth of cut. The arm 28 is then oscillated so as to cause the surface of the tooth to pass transversely of the cutting surface of the

115 wheel 9 and back again; the cutter is then rotated one tooth and the operation repeated until each tooth has been ground. In this manner all of the teeth are ground exactly alike and the operation can be quickly performed.

In practice the cutters are made 120 with a few angles only, among which 15, 30, 45 and 60 are the most prevalent, and if cutters having different angles are made they

125 are so rare as to be almost unknown, therefore, by means of my simple machine it is safe to say that any cutter of usual size and shape can be ground. By means of bushings such as 53 and 54, it is possible to make provision for handling cutters having any sized central opening and any length. The holes

51 and pins 52 make it possible to quickly and accurately adjust the parts to accommodate cutters having any of the usual angles. This machine is to a great extent a duplicate of the machine shown, described and claimed in my copending application, Serial No. 57,105, filed September 18, 1925, but differs from it by having incorporated therein means specifically intended for the support of cutters and 10 it is to this modified construction that the claims presented herewith have been directed.

In the preceding parts of this specification reference has been made to 45, 30 and 60 degree cutters. In order to make it clear what 15 is meant by this, applicant has indicated the sixty degree angle in Figure 5 by the letter W. These angles are the angles that the cutting edge of the teeth makes with a plane perpendicular to the axis of rotation of the cutters, and cutting said axis at right angles. 20

It will be noted that the pawl or stop 47 has no adjustment relative to its supporting rod 45. This simple matter has considerable bearing on the successful operation of my machine. In the grinding of cutters, it is essential that the angle that the cutting edge of the teeth makes with the axis of the cutter shall be accurate. With the arrangement of parts shown and described in this application, this angle cannot be altered when the parts are once adjusted because the pawl, tooth or stop 47 is in a fixed position. As before explained I obtain the desired clearance by raising the center of the cutters above the 25 horizontal center of the grinding wheel and providing the stop 47, which positively locks the cutting edge of the teeth at a predetermined level. If, for instance, the stop 47 could be adjusted, the operator might vary 30 the clearance by varying this stop, but such variation would change the angle of the cutter and thereby make it impossible to predetermine the setting of the machine so as to obtain the desired angle, for this angle depends on two variables, namely, the horizontal 35 level of the cutting edge and the angular relationship of the axes of the cutter-supporting bearing and the plane of the grinding wheel. By so constructing my machine that the stop 47 cannot be adjusted, accurate results may be obtained by any unskilled operator, as the accuracy does not depend on the skill of the operator but is predetermined by the construction of the machine. 40

Having now described my invention what I claim as new is:

1. A cutter grinder comprising a grinding wheel, a rotatably adjustable column mounted in suitable proximity to the wheel and provided with a plurality of bearings adapted 60 to receive cutters of varying angles, the axes of the bearings lying in a plane perpendicular to the axis of rotation of the column, said axes being variably positioned with reference to the axis of the column, so that the respective

cutters may be brought into proper relation with the grinding wheel, and means for varying the distance between the grinding wheel and column to carry the work into and out of grinding position. 70

2. A grinding machine comprising a grinding wheel, a rotary support mounted in proximity to the wheel and movable bodily toward and away from the wheel, the said support carrying a column whose axis coincides with the axis of the support, the column being provided with a number of bearings disposed therearound and whose axes all lie in a plane perpendicular to the axis of the column, the said bearings being respectively adapted to receive cutters of varying angles, the axes of the bearings being so disposed that when the cutters are mounted thereon, each cutter may be brought into proper grinding relation with the wheel, the axes of the bearings, except 80 one, being nonradial to the axis of the column. 85

3. The combination with a grinding wheel, of a support movable bodily toward and away from the periphery of the grinding wheel and mounted to rotate about its own axis in a 90 plane perpendicular to the plane of rotation of the wheel and to oscillate on an axis lying in a plane passing through the center of the wheel and cutting its axis at right angles, the support having a column whose axis coincides 95 with that of the support, the column having bearings disposed therearound, whose axes all lie in a plane perpendicular to the axis of the column, the bearings being located at different distances from the axis of the support, 100 one in a line radial to said axis and others in lines non-radial thereto, whereby said bearings are adapted to receive cutters of varying angles, the axes of the bearings being so disposed that each cutter may be brought into 105 grinding proximity to the wheel, the axes of the bearings, except one, being nonradial to the axis of the column.

4. In a cutter grinder the combination of a grinding wheel, a rotatable support adjacent 110 the wheel and movable bodily toward and away from the same, the said support being mounted to oscillate on an axis lying in a plane passing through the center of the grinding wheel and cutting the axis of the wheel at 115 right angles, the support having a turret-like column whose axis coincides with that of the support, the said column having bearings disposed therearound whose axes all lie in a plane cutting the axis of the column at right angles, 120 the said bearings being adapted to receive cutters of varying angles, the axes of the bearings, except one, being nonradial to the axis of the column, and so disposed that each of the 125 bearings may be moved into position to grind the cutter carried thereby.

5. In a cutter grinder the combination with a grinding wheel of an arm mounted to oscillate on an axis lying in a plane passing through the center of the grinding wheel and 130

1 cutting the axis of the wheel at right angles, a support mounted to rotate about its own axis on the oscillatory arm, its plane of rotation being parallel to the axis of oscillation of the
 5 arm, the support being provided with a column whose axis coincides with that of the support, the said column having bearings disposed therearound whose axes all lie in a plane perpendicular to the plane of rotation
 10 of the grinding wheel, the bearings being adapted to receive cutters of varying angles, the axes of the bearings being so disposed that each cutter carried thereby may be brought into grinding relation with the wheel, the
 15 axes of the bearings, except one, being non-radial to the axis of the column.

6. In a grinder of the class described, the combination of a grinding wheel, an oscillatory support mounted in suitable proximity
 20 to the wheel, its axis of oscillation being in a plane parallel to the central plane of wheel rotation when the support is in the vertical position, the support having a column whose axis coincides with the axis of the support,
 25 the column being rotatable about the axis of the support and having bearings disposed therearound and adapted to receive cutters of varying angles, the axes of the bearings lying in a plane cutting the axis of the column
 30 at right angles, the axes of certain of the bearings being offset from the axis of the column so that the cutters may be successively brought into such relative position to the grinding wheel that the central plane of rotation of the wheel shall bisect the teeth of each cutter when the support and column are in the upright position and means for moving the work into and out of contact with the grinding wheel.

40 7. In a grinder of the class described, the combination of a grinding wheel, a support adjacent to the wheel and movable bodily toward and away from the periphery of the wheel in the central plane thereof and including a column in turn-table connection with the support and adapted to be rotatably adjusted about an axis off-set from the plane of bodily movement of the support and parallel thereto, said column provided with work
 45 supporting bearing pins in a plane normal to said axis, the axes of certain of the bearings being in nonintersecting relation with the axis of the column, so that the different cutters may be successively brought into proper grinding relation with the wheel and so that the central plane of rotation of the latter shall normally bisect the teeth of the various cutters and means for moving the work into and out of contact with the grinding wheel.

55 8. In a grinder of the class described, the combination of a grinding wheel, a set of rotatably adjustable work supports mounted in suitable proximity to the wheel, their plane of rotation being normally perpendicular to that of the wheel and above that of the wheel

axis when the support is in the upright position, said work supports having bearings adapted to receive cutters of varying angles, the axes of the bearings all lying in a plane cutting the axis about which the work supports are adjusted at right angles, the bearings having shoulders arranged at varying distances from the said axis so that the cutters of different size carried by the respective bearings may be successively brought into
 70 75 grinding relation with the wheel and means for moving the work into and out of contact with the grinding wheel.

9. A machine for grinding cutters, comprising, in combination, a base, a grinding wheel supported from the base and adapted to be rotated about an axis located above said base, a motor secured to the base, means for transmitting power from the motor to the wheel for rotating the latter, an arm mounted
 80 for oscillation about an axis that lies below the axis of the grinding wheel and which lies in the plane of rotation of said wheel, a turret head secured to the upper end of said arm, means for permitting said head to rotate about an axis perpendicular to the axis of oscillation of said arm, said turret head having a plurality of bearings extending outwardly in a plane perpendicular to said axis and means for clamping the head against rotation on the arm.

10. A machine for sharpening cutters, comprising, in combination, a rotatable grinding wheel, and means for supporting a cutter while being ground, said means comprising an oscillatory arm adapted to swing about an axis lying in the plane of rotation of the grinding wheel, a stud extending upwardly from said arm, a turret head rotatably secured to said stud, means for locking said head against rotation about said stud and bearings extending outwardly from said head, said bearings having their axes in a plane perpendicular to the axis of the stud, said bearings being each adapted to receive and support a
 105 cutter.

11. A machine for sharpening cutters, comprising, in combination, a rotatable grinding wheel, and means for supporting a cutter while being ground, said means comprising an oscillatory arm adapted to swing about an axis lying in the plane of rotation of the grinding wheel, a stud extending upwardly from said arm, a turret head rotatably secured to said stud, means for locking said head against rotation about said stud, bearings extending outwardly from said head, said bearings having their axes in a plane perpendicular to the axis of the stud, said bearings being each adapted to receive and support a cutter and means for adjusting said arm towards and away from the periphery of the grinding wheel.

12. In a grinding machine for sharpening cutters, in combination, a grinding wheel;

means for rotating said wheel, a supporting arm mounted for oscillation about an axis lying in the plane of rotation of said grinding wheel, a turret head secured to said arm, 5 said head being mounted for rotation about an axis that is perpendicular to the axis of oscillation of said arm, a plurality of shafts extending outwardly from said head, said shafts having their axes in a plane perpendicular to the axis of rotation of said head, said plane lying above the axis of rotation of the grinding wheel when the plane is in its uppermost position, and means for moving 10 said supporting arm towards and away from the grinding surface.

13. In a grinding machine for sharpening cutters, in combination, a grinding wheel, means for rotating said wheel, a supporting arm mounted for oscillation about an axis 20 lying in the plane of rotation of said grinding wheel, a turret head secured to said arm, said head being mounted for rotation about an axis that is perpendicular to the axis of oscillation of said arm, a plurality of shafts 25 extending outwardly from said head, one of said shafts being radial to the axis of the head and the others being respectively tangential to circles concentric with said axis and of differing diameters, said shafts lying 30 in a common plane parallel to and offset from a plane which includes the grinding wheel axis when the supporting arm is at the center of its arc of oscillation, said arm being adjustable toward and away from the grinding 35 wheel and each of said shafts being adapted to support a cutter in position for contact with the grinding wheel.

14. In a machine for grinding rotary cutters, the combination with an oscillatory support, of a rotatably adjustable work holding 40 turret mounted thereon, means for limiting the arc of oscillation of the support, a series of cutter mountings on the turret each having an axis in the same plane but angularly 45 divergent from the others with only one of said axes corresponding to a radius of the turret axis and each adapted by turret adjustment to hold one type of cutter with the working edges of its blades in positions for

successive registry with a single grinding 50 line, and a grinding wheel having a transverse line of its periphery coinciding with said grinding line.

15. In a machine for grinding rotary cutters, the combination with an oscillatory support 55 including a turn-table having its axis at one side of and parallel to a plane which includes the axis of oscillation, of a rotatably adjustable work holding turret supported from the turn-table for rotation about the 60 axis thereof, means for limiting the arc of oscillation of the support, a series of cutter mountings on the turret some of which 65 mountings have axes non-radial to the axis of the turret and each adapted by turret adjustment to hold one type of cutter with the working edges of its blades in positions for successive registry with a single grinding 70 line, and a grinding wheel having a transverse line of its periphery coinciding with said grinding line in a plane which includes the axes of the cutters and which is parallel to a plane which includes the axis of said wheel.

16. In a machine for grinding rotary cutters, the combination with a grinding wheel, 75 of a support mounted to oscillate in a plane parallel to the grinding wheel axis and across the central plane of the grinding wheel, a turret mounted upon said support with its 80 axis parallel to said plane and off-set therefrom, said turret having a turn-table member provided with means for securely anchoring the turret to the support in different positions of rotative adjustment about said axis, 85 said turret having shouldered projections eccentrically disposed, and provided with arms to support cutters, the blades of which 90 differ in angular pitch, said arms being positioned to support their respective cutters, each with the working edges of its blades in position for successive registry with a transverse line in the periphery of the grinding wheel, when the cutter is rotatively adjusted 95 thereon.

In testimony whereof I affix my signature.

HARRY G. MILLER.
